UNITED STATES PATENT OFFICE

CHARLES F. BERRY, OF BOSTON, MASSACHUSETTS

COMBINED RUBBER AND LEGGING

Application filed November 11, 1930. Serial No. 494,903.

This invention relates to combined rubbers and leggings forming a wading boot particularly adapted for the use of women, and has for its object the production of a rubber 5 having an upward extension fitting the leg of the wearer and made of thin material adapted to be rolled, this material preferably being stretchable.

This object is attained in the article illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization 15 of these instrumentalities as herein shown and described except as required by the scope of the appended claims.

Of the drawing:

Figure 1 represents an elevation of a combined rubber and legging shown upon a leg.

Figure 2 represents a similar elevation showing the legging rolled down about the ankle.

Figure 3 represents an enlarged elevation 30 of the rubber and showing in section the lower portion of the legging attached thereto, and

Figure 4 represents a vertical section on line 4, 4, on Fig. 1.

Similar characters indicate like parts throughout the several figures of the drawing.

In the drawing, 10 is a rubber shoe which may be of any well known construction or 40 shape.

To the upper part 11 of the rubber shoe is secured the lower end 12 of a legging 13 shaped to fit the leg of the wearer.

The legging 13 is preferably made of thin 45 stretchable material such as rubber.

When on the leg and extended its full length, the legging 13 will cover most of the stocking 14 on the leg and protect it from being discolored by splashes of mud and 50 water from passing vehicles.

The bottom 12 of the legging 13 is cemented, vulcanized or otherwise secured to the outside of the upper portion 11 of the rubber 10, as shown in the drawing.

This legging 13 may be of any color desired but preferably is of the same color as that of the stocking worn by the wearer.

When in the extended position shown in Fig. 1, the rubber and legging is watertight and makes it possible for the wearer to wade 60 in streams as is often necessary in fishing and other sports.

The wearer can also wade through deep puddles without wetting the feet and 65 stocking.

The upper end of the legging 13 is provided with a flap 15 turned inwardly and downwardly as indicated more clearly in Fig. 4 and the lower edge of this flap 15 is cemented, vulcanized or otherwise secured 70 to the inner face of said legging.

Between the legging 13 and flap 15 is disposed a garter 16 of material having a greater degree of resiliency than that of the legging itself, and therefore is disconnected 75 from the legging being loosely confined in the upper edges thereof.

When the legging 13 is extended as in Fig. 1, the garter 16 will retain it in place without binding on the leg and the legging itself 80 will stretch only enough to conform to the shape of the leg without wrinkles.

When it is unnecessary to have the legging extended its full length, it may be rolled 85 downwardly about the ankle as shown at 17 in Fig. 2, leaving the stocking 14 exposed and giving the appearance of an anklet sock worn over the stocking 14.

Obviously, the stocking may be rolled 90 downwardly on the leg to any point intermediate the top of the legging and the ankle and the resilient garter 16 will retain the roll at any position desired.

The legging 13 may be made tubular and 95 then secured to the rubber shoe 10, or it may be made from a flat piece suitably shaped and then seamed by having its opposite edges cemented, vulcanized or otherwise secured together.

The legging 13 may be made attached to 100

the rubber or it may be sold with cement on the inner face of its lower end ready to be stretched over any rubber shoe and then secured thereto by said cement.

The material of the legging 13 is so thin that when not in use it may be rolled down within the rubber shoe 10 and occupy very little space when stored in a closet or being carried in a suitcase or the like.

- 10 Being made of such thin material the legging when applied to the rubber shoe adds very little to the weight of the rubber shoe itself.

It is self-evident that the combined rubber shoe and legging has all the advantages of a much heavier rubber boot while it has many advantages not possessed by a rubber boot.

For instance, the leg of a rubber boot is continually flapping about the leg which is 20 very objectionable, while the present legging fits the leg and overcomes this objection.

A rubber boot is heavy and the present article is very light in weight and while the rubber boot occupies considerable space, the 25 space that the present article occupies is reduced to a minimum.

No comfort can be obtained by wearing a rubber boot over an ordinary shoe while the present article may be worn over the wearer's shoe with no discomfort.

30 It is believed that the many advantages of the present invention will be understood readily without further description.

Having thus described my invention, I 35 claim:

As a new article of manufacture, a wading boot consisting of a rubber shoe having a high upper adapted to enclose the entire foot of a wearer and having hermetically secured 40 to said upper well above the sole of the shoe a tubular leg covering composed of seamless stretchable material adapted to fit closely over the leg of the wearer and provided with an inturned upper end in which an elastic 45 garter is loosely confined.

Signed by me at 294 Washington Street, Boston, Massachusetts, this 8th day of November, 1930.

CHARLES F. BERRY.
